FIG. 2

FIG. 3

FIG. 1 is a right side elevational view of a side panel unit for a vehicle showing our new design;

FIG. 2 is a front quarter perspective view of a portion of the side panel unit shown in FIG. 1 showing how the various front surfaces are formed and how the surfaces are related in terms of planes, one to the other; and

FIG. 3 is a rear quarter perspective view showing how the various rear surfaces are formed and how the surfaces are related in terms of planes, one to the other.

The portion in broken lines is shown for illustrative purposes only.

This is a divisional application of application Ser. No. D. 13,630, filed Sept. 20, 1968.

We claim:

The ornamental design for a side panel unit for a vehicle, as shown and described.
